UNITED STATES PATENT OFFICE.

CORNELIUS VANDERBILT, OF NEW YORK, N. Y.

LOCOMOTIVE FIRE-BOX.

SPECIFICATION forming part of Letters Patent No. 787,241, dated April 11, 1905.

Original application filed December 17, 1900, Serial No. 40,182. Divided and this application filed March 3, 1902. Renewed September 17, 1904. Serial No. 224,859.

To all whom it may concern:

Be it known that I, CORNELIUS VANDERBILT, a citizen of the United States, residing in the borough of Manhattan, in the city of New York, county and State of New York, have invented certain new and useful Improvements in Locomotive Fire-Boxes, &c., of which the following is a specification, this application being a division of application, Serial No. 40,182, filed December 17, 1900.

This invention relates generally to furnaces for boilers, and more especially to furnaces adapted for use in connection with water-tube boilers.

The invention is illustrated in the accompanying drawings as embodied in a structure which is specially designed for use upon or as a part of a locomotive having a water-tube boiler; but it will be understood that various features of the invention possess utility without reference to their use with the particular type of boiler shown or in a locomotive and that the several features of improvement are not necessarily associated with one another in a common structure, but that some of the features are capable of use independently of others.

The invention will be fully described hereinafter with reference to the accompanying drawings, in which—

Figure 1 is a partial side elevation of a locomotive equipped with the improved furnace. Fig. 2 is a general perspective view of the framework of a locomotive shown in Fig. 1. Fig. 3 is a longitudinal central section through the fire-box section of a locomotive. Fig. 4 is a longitudinal central section through the forward part or smoke-box section of a locomotive. Fig. 5 is a view of a locomotive shown in Fig. 1, partly in rear elevation and partly in section on the line V V of Fig. 1. Fig. 6 is a transverse section on the line VI VI of Fig. 1. Fig. 7 is a transverse section on the line VII VII of Fig. 1.

The scale of Figs. 3 to 7 is larger than that of Figs. 1 and 2.

In order that the functions of the several features of the improved furnace may be read-

ily understood, the general construction of the boiler, as well as of the supporting-frame-work of the locomotive, will be described.

As shown in Figs. 1 and 2, the main frame upon which the boiler is supported comprises side bars 1, having upper chords 2 3 and axle yokes or pedestals 4 for the axles 5 of the wheels 6. The side bars 1 are tied together by cross-bars, as at 7, of any suitable construction. The front end of the frame is supported by a pony-truck, the wheels 8 and axles 9 of which are indicated in dotted lines in Fig. 1.

The intermediate frame by which the boiler is directly supported comprises two longitudinal girders 10, rigidly supported upon the main frame by chairs or castings 11 12 and tied transversely by three struts—a forward strut F F, an intermediate strut D D just forward of the fire-box section, and a rear strut B B just forward of the rear ends of the girders. The intermediate frame is held rigidly to the main frame at its end by the chair 12 and by its connection with the cylinder-casting through the cylindrical smoke-box. Both chairs 11 and 12 are rigidly secured to the chords of the main frame.

The rear strut B B, Figs. 2, 3, and 5, is built up of the central compression-web 23, strengthened and stayed by suitable angle-irons, and supports at its top a cradle for the two drums of the boiler, hereinafter to be referred to, such cradle comprising a flat plate 32, curved upwardly at its ends, and an intermediate chair or casting 34, the base 37 of which is provided with longitudinal apertures 39 for the bolts 40, by which the chair is secured to the plate 32 so that it may move thereon longitudinally.

The strut D D (shown in Figs. 2, 3, and 6) likewise comprises a central or compression plate 50, strengthened and stayed by suitable angle-irons and having an aperture 53 for the passage of the products of combustion. This strut is supported upon and secured to the side girders 10, and itself supports cradles for the boiler-drums, such cradles comprising end chairs 65 and a central chair 69, which is also

adapted for longitudinal movement, as described with reference to the central chair of the strut B B.

The strut F F (shown in Figs. 2 and 4) comprises a base-plate 84, secured to the side girders 10, plate-posts 85, and a plate or casting 87, the latter, with the plates 85, forming the chair 12. The main compression-plate 95 of this strut rests upon the base-plate 84 and is firmly secured thereto. It is formed with an aperture 99 for the passage of the products of combustion and at its top supports the cradle base-plate 100, the ends of which are curved upwardly. A central chair 107 is secured to the base-plate by bolts which pass through transverse slots in the lower web to allow of lateral movement.

The boiler or generator with which the furnace is herein shown as combined comprises a pair of longitudinal drums, side headers located transversely farther apart than the two upper drums and at a lower level, both drums and the side headers having substantially the same longitudinal extension, and a lower or intermediate header located below the plane of the side headers and centrally. The upper drums 124 find their support on the struts B B, D D, and F F, the intermediate frame directly supporting them and their appurtenant weight. They are preferably secured rigidly to the front strut and flexibly to the rear and central struts to allow of relative movement. The steam-space of the drums is connected by a series of short pipe-sections 125 with a cylindrical dry pipe 126, closed at the rear end by a cap 127 and supported between the drums on chairs 128, as shown in Figs. 3 and 6, which rest between and on the drums. The front end 129 of the dry pipe 125 extends into the smoke-box 130 and downwardly to the throttle-box 131, from which extend the branch pipes 132 to the cylinders 133, as shown in Fig. 4. As is customary in locomotive practice, the front end of the frames and cylindrical smoke-box section are secured together by casting 125^a, which is the same as is usually provided for this purpose. The side headers 134 terminate substantially within and at the front of the rear strut B B, Fig. 3, and are connected, respectively, with the lower half of the corresponding drums at one side of the vertical axis thereof, Fig. 6, and to the rear of the strut D D, or, in other words, within the precincts of the fire-box, by a gang of water-tubes 135, Fig. 6, disposed in reverse-curve form, having horizontal outwardly-extending sections 136, vertical sections 137, and lower and outer ends 138, converging to the side headers 134, the upper ends 136 entering the lower half of the corresponding drum and all located substantially away from or outside of the opening 53 through the strut D D, said tubes being in vertical and horizontal series or in banks not so regularly placed.

Immediately forward of the central strut D D the boiler-tubes are not only arranged in vertical and horizontal series or banks, but have a twofold or duplex disposition.

By reference to Figs. 6 and 7 it will be noted that the tubes 139, extending between the lower half of each upper drum 124 and the tube-sheet 140 of the lower intermediate header 141, are substantially straight up and down and form a bank immediately in front of the opening 53 through the strut D D to at once engage the products of combustion in the passage thereof from the fire-box to the smoke-box and that the disposition of the tubes 142 between the lower half of each drum 124 and the tube-sheet 143 of the side headers 134 is the reverse of the tubes 135 in that the vertical portions 144, Fig. 6, form a head 145 in front of the opening 53 and then extend outwardly at 146 to the tube-sheet 143, which latter extends between those parts to the rear of the strut D D.

The arrangement of tubes, drums, and headers, as will be seen by reference to Figs. 6 and 7, substantially fills up transversely and longitudinally the entire channel which is formed for the passage of the products of combustion between the struts D D and F F, thereby practically filling up the entire central or intermediate section of the locomotive with water-tubes adapted to be directly engaged by the products of combustion.

To furnish air for combustion, holes 24 are cut through the web-plate of the support B B about nine or ten inches above the casting. The air which is supplied beneath the fire passes through the holes and through the dampers in the ash-pan to the under side of the grate. The air which is admitted over the grate passes through the fire-doors or dampers which may be placed in the fire-doors and are not shown in the drawings.

The course of the products of combustion is over the fire-brick arch, through the opening in the second strut or support, the iron plate of which is protected by fire-brick, (and preferably a little asbestos lagging between the fire-brick and the plate,) between the tubes which connect the bottom or central header with the drums, and also at the sides between the tubes from the side headers. The spacing of the tubes is such that at the center, where the exhaust of the engine would naturally produce the greater draft, the tubes are placed close together, and at the sides, where the draft may be expected to be less, the tubes are placed farther apart, with the intention of equalizing as far as possible and spreading out to the greatest extent practicable the products of combustion, so that all of the heat developed by the coal may be utilized for the production of steam. The water must be fed to the boiler at such a place that it does not interfere with the free circulation. This may be accomplished by feeding at either end of

the drums or at either end of the headers or centrally in the top drum at the location of the center strut if the temperature at this point permits.

Fire-brick may be employed to protect the parts in the interior, where the heat is intense. In the fire-box section this is disposed along the sides, as shown in section in Fig. 6, and comprises vertical portions 315, having the lower thick and outwardly-extending portion 316 and inclined curved portions 317, all being secured against the inside of the sheathing and its framework before described in any usual or desired manner. Between the drum-supporting struts in this section hollow fire-brick 318 are placed between the crown-lining 317 and the outer flanges 149 150 of the drums to prevent the products of combustion from passing above the drums. These sections of brick may all find support at their ends in the framework of the struts and in any other desired way.

The opening 53 in the strut D D, leading into the intermediate chamber, is lined with fire-brick, as indicated in Fig. 3, that at the bottom, 319, being extended over and about the upwardly and rearwardly inclined plate 79 to form the fire-box deflector or arch and finding a seat on the shelf 75 of the channel-bar 74. This lining extends forward through the opening in the strut and turns down, as at 320, over the sheath or covering 80 to the plate 211. Similar brick linings 321 322 are provided for the top of the opening to cover the angle-irons 64 and adjacent plate. Such lining may also be extended over and about all the exposed parts of the framework or wherever desired.

Within the intermediate section the vertical sides 248 of the sheathing-box on each side of the lower header are lined with brick 323, Fig. 7, while the heat is confined so as to strike the tubes 142 on the lower side of the bank by means of hollow quadrangular bricks 324, resting at each side on the upper corner of the sheathing and frame 325 and against the angle-plate 326, which is supported by a plate 327, riveted to the vertical web 328 of a sheathing-bracket 328^a, carried by the plate 250^a. A horizontally-disposed layer 329 is carried by said plates 328 or by the horizontally-disposed plate 327^a carried thereby, and an additional brick 330 is employed to reach over the top of the girder 10 to the side sheathing 225. Above the side headers the vertical plates 226^a are extended lower than the horizontal plates 226^a, as at 331, and have riveted to their lower edges the inwardly-projecting angle-irons 332, which form supports for fire-brick lining above the header and tubes, such lining consisting of the hollow triangular portion 334, having the vertical wing 335. Upon this is another strip, 336, following the contour of the tubes and fitting closely against the outward flanges 149 150 of the drums 124.

A lining of fire-brick may also extend over the drums inside the crown-sheathing. It will be noticed that this lining about the headers and drums follows in general the curvature of the tubes and that considerable material is saved by the hollow construction of the brick. 70

Fire-brick may also be placed about the exposed portions of the strut F, as indicated in Fig. 4, the bottom part 400 extending through the opening and down on each side, as at 401 75 and 402, and being slanted off, as at 403, into the smoke-box. The upper part 404 extends through and upward, as at 405, to cover the edges of the hole and framing and may extend about the whole circumference of the 80 opening, as indicated by the numeral 406.

It will of course be understood that the described disposition of the fire-brick is by no means the only one that could be utilized; but for many purposes it is considered preferable. 85

The ash-pan 49 beneath the fire-box, Figs. 3 and 6, comprises a rectangular box-like base or bottom 250, having vertical sides and being sufficiently narrow to fit between the side frames 273 of the truck. It is provided with end apertures having swinging doors 251 to close the same. The lower longitudinal corners of the same are formed with bars 252, grooved on their opposing faces to receive the bottom sheet 253, the side sheets and end door-frames being suitably secured thereto by means of angle-irons. The bottom of the pan is arched at 254 to raise it out of possible contact with the axle, and at its forward end a 100 hole 255 is provided, with a sliding cover 256 therefor. Access to the pan for any purpose may thus be had at either end or through the aperture 255. This box is supported from the rear and intermediate struts and the side 105 girders of the intermediate frame and receives the ashes from the whole grate area by the flaring or funnel-like sides 257 and corresponding ends 258, which are secured to the edges of the box by angle-plates 259 and by similar 110 plates 260 to the flanges 261 of the depending vertical webs 262 of the grate-supporting bars 262^a, which are secured to the side girders 10. The front end 258 is riveted at its upper edge to the angle-plate 78, bolted, as before described, to flange 77 of the transverse channel-casting 74 of the strut D D. The rear plate 258 is secured to the flanged iron 48, which is shown bolted to the channel-bar 45. The latter plate has apertures covered by the sliding 115 plates 263 to provide admission to the ash-pan from the rear through holes 24 in the transverse plate of the rear strut B B. The flaring sides 257 and ends 258 are tied together by corner angle-bars, so as to make a strong construction throughout. Boxes 257^a, Fig. 6, are built up, as shown, in the sides 257 of the ash-pan to provide room for the drive-wheels 6. 120

The grate 264^a, which may be of the usual construction and provided with the usual 130

dumping levers and rods extending to the rear and adapted to be operated from the cab, comprises four sections, which are supported at the sides on a projecting ledge 264 of the box and on channel-castings 264^a, secured to the side girders 10, immediately beneath the vertical web of the angle-irons 18. At the center a longitudinal bar 265 extends the length of the fire-box and is supported at its ends upon the framework in any desired manner, the grate-bars resting upon the horizontal webs 266 of said bar. The sections are separated transversely by a beam 265^a, located about midway of the box and secured at its ends to the framework by any suitable means. As shown, the grates are located above the drive-wheels of the locomotive and extend from side to side of the intermediate frame. They are also above the plane of the lower header 141. Filling or other bars 265^b are placed in front and rear of the grate.

The stoke-doors 280, Fig. 3, which are used to close the openings 25 are practically segments of spheres of appropriate size, having outwardly-bent or flat circular flanges adapted to fit closely against the flat rings at the edges of the holes in the plate 23. Suitable hinges 280^a are provided for the same at one side of the opening, and a catch 280^b is provided at the other, with which a latch on the door engages. The curved portions of said doors may be provided with openings 282, which may be closed by a plate 283 of suitable form fitting closely over the outside of said portion and adapted to be turned by a handle 284 to open or close the same. A disk or other deflector 285 may also be provided and supported on the door by a standard 286. Through these doors coal may be thrown to any part of the grate.

I claim as my invention—

1. In a furnace for steam-generators comprising a fire-box section and another section communicating therewith, a fire-brick deflector located at the lower edge of the opening between the sections and comprising a transverse plate or web secured to the frame and fire-brick placed about it on both sides.

2. In a furnace for steam-generators comprising a fire-box section and another section communicating therewith, a fire-brick deflector located at the lower edge of the opening between the sections and inclining inwardly and upwardly into the fire-box section, said deflector comprising a transverse web or plate secured to the frame and fire-brick placed about it on both sides.

3. In a furnace for steam-generators, the combination of a framework, a cross-strut and girders, a fire-box section and an intermediate section separated by said strut, an upwardly-inclined plate secured to said cross-strut, and a fire-brick covering for said plate.

4. In a furnace for steam-generators, the combination of a framework, a fire-box sec-

tion and another section, a transverse strut separating said fire-box section and other section and having an opening therethrough, and a deflector for the fire-box comprising an inclined plate attached to the strut of the lower side of the opening, a fire-brick covering for said inclined plate.

5. In a furnace for steam-generators, the combination of a fire-box section, an intermediate section, a frame, and a transverse plate to separate such sections supported by the frame and having an opening therethrough, the opening in said plate being lined with fire-brick.

6. In a furnace for steam-generators, the combination of a fire-box section, another section, a frame, a transverse strut on said frame separating the fire-box from the other section and having an opening therethrough for the passage of the products of combustion, and fire-brick applied to the exposed parts of said strut.

7. In a furnace for steam-generators, the combination of a fire-box section, a forward section, a grate in the fire-box section, and a heating-surface in the other section, a wall separating the two sections and having an opening therethrough, and fire-brick covering the entire lower edge of the opening from the grate on one side through the opening to the heating-surface on the other side for protecting the frame and co-operating devices.

8. The combination of a frame, a boiler carried thereby, a smoke-box section and another section, a partition therebetween having an opening through which the products of combustion are adapted to pass, and a fire-brick lining for said opening.

9. The combination of a frame, a generator carried thereby, a fire-box section, a smoke-box section, and an intermediate section, partitions between the latter section and the others having openings therethrough for the passage of the products of combustion, and fire-brick linings for said openings.

10. The combination of a frame having cross-struts, a steam-generator carried by said struts and frame and comprising a lower header suspended beneath the struts, the said struts having openings therethrough for the passage of the products of combustion, and a fire-brick lining for said openings extending down on the sides of the struts to the said header, and over the exposed portions on the other sides of the struts.

11. The combination of a frame having cross-struts, a generator having a header, the said struts having openings for the passage of the products of combustion, devices to support said header located on said struts beneath the opening, and fire-brick linings for said openings extending over the said devices.

12. In a locomotive, the combination of a frame, a generator supported thereby, a sheathing also supported by said frame and com-

prising vertical side plates, horizontal plates attached to the vertical plates above their lower edges, angle-irons secured to said lower edges, and a fire-brick lining for said horizontal and vertical plates and supported by said angle-irons so as to project inward.

13. In a locomotive, the combination of a frame comprising side girders, a fire-box extending the full width of said girders, longitudinal supports secured to said girders con-

sisting of channel-bars having supporting-edges formed in the upper and inner edges thereof, and grates extending between said supports and resting in such ledges.

This specification signed and witnessed this 15
first day of March, A. D. 1902.

CORNELIUS VANDERBILT.
